ABSTRACT: A single-bucket excavator comprises a boom with a grip mounted thereon and turnable about its longitudinal axis. A bucket is mounted on the grip and is suspended on movable pulleys of two double pulley block and tackle systems containing a balancing system which transmits loads to the boom via a spring-loaded friction device.

FIG. 4

**STRAIGHT-SHOVEL-TYPE WORKING EQUIPMENT OF
A SINGLE-BUCKET EXCAVATOR**

The present invention relates to single-bucket excavators, and more particularly to equipment of the "straight-shovel" type. Most particularly, the invention relates to working equipment wherein a support or "grip" has a bucket fixed thereto and suspended on two pulley blocks, the grip and bucket being so mounted that they are not fixed against rotation about the longitudinal axis of the grip. In known equipment of this type, the pulley blocks for bucket suspension are independent of each other.

Despite a number of advantages which said known equipment has over other arrangements of the "straight-shovel" type, it fails to provide uniform distribution of loads among the pulley blocks.

The said disadvantage necessitates an increase of rope diameter, as well as a greater weight of the hoisting winch and metal parts of the excavator.

It is an object of the present invention to eliminate the disadvantage of the aforescribed equipment.

This object is accomplished in the aforescribed type of equipment by interconnecting the ends of the pulley block ropes on a link providing for balancing the loads among the pulley blocks.

When operating on rocky terrain, it is preferred to equip the link providing for the balancing of the loads with a resilient absorbing device to reduce the dynamic loads thereof.

It is also preferred to dispose the movable pulleys of the pulley blocks in the plane of the bucket rocker to prevent the displacement of the ends of the pulley block ropes on the aforesaid link, which displacement may take place when the bucket with the grip or handle turns about the longitudinal axis of the latter, with the cutting edge of the bucket being nonuniformly loaded.

In order to decrease the turn angle of the bucket with the grip or handle about its longitudinal axis, the axis of the movable pulleys of the pulley blocks is made stationary with respect to the bucket in the plane of its rocker, this making the bucket more stable.

The following detailed description of one embodiment of the invention is given with reference to the accompanying drawings, wherein:

FIG. 1 is a schematic view of an excavator provided with straight-shovel-type working equipment made in accordance with the invention;

FIG. 2 is a schematic diagram of the winding of the hoisting mechanism ropes of the equipment of FIG. 1;

FIG. 3 is a suspension unit of the bucket in the equipment of FIG. 1; and

FIG. 4 is a mounting unit for the resilient absorbing device in the equipment of FIG. 1.

The working equipment of the invention consists of a boom 1 (FIG. 1), a single-beam grip or handle 2 mounted on said boom in such a way that it is not fixed against turning about its longitudinal axis, and a bucket 3 mounted together with said grip and suspended on two double pulley blocks 4 and 5 (FIG. 2).

Movable pulleys 6 and 7 of the pulley blocks are disposed in the plane of the bucket rocker 8 (FIG. 3).

The axle 9 of the pulleys 6 and 7 is stationary such that the carrier in which it is mounted cannot pivot with respect to the bucket in the plane of the rocker 8, that is, the rocker 8 couples axle 9 to bucket 3 so that a plane perpendicular to bucket 3 always passes through axle 9 even though axle 9 can tilt relative to grip 2.

The ends of the ropes of the pulley blocks 4 and 5 are interconnected at and form a continuous member to embrace a guide 10 (FIGS. 2 and 4) which is essentially a link providing for balancing the loads among the pulley blocks. The semipulley or guide 10 transmits the load to the boom 1 through a spring-loaded friction device 11 disposed in a housing 12 rigidly secured on said boom in whose guides the semipulley 10 is mounted.

The spring-loaded friction device 11 consists of a pressing

15 spring 16, a cup 17 and a coupling bolt which is provided with a nut 18, by means of which the device may be adjusted in advance for a required load.

20 A rubber, hydraulic or other such similar device may be used as the resilient, absorbing device.

When hanging new ropes for the pulley blocks, the semipulley 10 provides for complete balancing of the loads between the pulley blocks, said balancing being maintained for all further cases of bucket loading as may occur in the course of digging.

25 The pulleys 6 and 7 are disposed in the plane of the bucket rocker 8. In case the cutting edge of the bucket is nonuniformly loaded and said bucket together with the grip 2 turns about its longitudinal axis, the pulleys 6 and 7 roll along the ropes of the pulley blocks.

30 As the axle 9 of the movable pulleys of the pulley blocks is stationary with respect to the bucket as described above the angle of turn of the bucket and the grip about the longitudinal axis of the latter is reduced, which provides for a greater stability of the bucket.

35 When operating in rocky soils, the improvement proposed herein makes it possible, due to the employment of the spring-loaded friction device 11, to considerably reduce dynamic loads.

40 When loads are greater than those for which spring-loaded friction device is adjusted, the semipulley 10 provides for a displacement of the pressing cone 13 which, acting upon the wedges 14, makes the latter draw together and move inside the cup 17 provided in this zone with an inner tapered surface. The load transmitted from the wedges 14 and spring 16 to the cup 17 is received by the housing 12 rigidly connected to the boom 1.

45 Sixty to ninety percent of the energy of moving masses, transmitted to the device 11, is absorbed due to the nonreversible work produced by the friction forces of the wedges 14 along the cup 17, pressing cone 13 and pressing washer 15.

For an effective operation of the resilient, absorbing link it is necessary that the latter should remain resilient at maximum possible loads.

What is claimed is:

1. Apparatus comprising a boom, an elongated handle in intersecting relation with said boom, said handle being rotatably supported on said boom about the longitudinal axis of said handle, a bucket fixed to said handle and being capable of turning movement together with the handle about the longitudinal axis of the latter, and pulley means for operating said bucket, said pulley means including pulleys coupled to said bucket, a resilient link affixed to said boom, and lines encircling respective of said pulleys and looping around said link to absorb displacement of said bucket.

2. Apparatus as claimed in claim 1, wherein said lines have ends interconnected at said link and other ends, comprising means to wind up and release said other ends.

3. Apparatus as claimed in claim 1, wherein said pulleys are coaxial and have an axis extending transversely of a plane fixed relative to said bucket, said apparatus further comprising a rocker means having an extent defining said plane and coupling said pulleys to said bucket to allow the axis to pivot, within a further plane transverse of said first-named plane, relative to said bucket.

4. Apparatus as claimed in claim 3 wherein said pulleys are arranged substantially in said first-named plane.

5. Apparatus as claimed in claim 1 wherein said resilient link includes a guide element, and a spring-loaded device resiliently connected to said guide element.

6. Apparatus as claimed in claim 5 wherein said spring-loaded device includes a housing, a pressing member, means supporting said guide element, and a spring interposed between said pressing member and said housing for urging said pressing member toward said guide element.

7. Apparatus as claimed in claim 6 including wedge means in said housing and a conical member interposed between said wedge means and guide element.
